US00D787006S

(12) **United States Design Patent** (10) **Patent No.:** **US D787,006 S**
(45) **Date of Patent:** **** May 16, 2017**

(54) **CYLINDER RELEASE BUTTON FOR A REVOLVER**

(71) Applicant: **Kimber IP, LLC**, Yonkers, NY (US)

(72) Inventors: **Daniel Edward Sapiro**, Mount Vernon, NY (US); **Ronald Richard Dudzic, Jr.**, Tarrytown, NY (US)

(73) Assignee: **Kimber IP, LLC**, Yonkers, NY (US)

(**) Term: **15 Years**

(21) Appl. No.: **29/551,878**

(22) Filed: **Jan. 18, 2016**

(51) LOC (10) Cl. **22-01**

(52) U.S. Cl.

USPC **D22/108**

(58) **Field of Classification Search**

(57) **CLAIM**

The ornamental design for a cylinder release button for a revolver, as shown and described.

DESCRIPTION

FIG. 1 is a front, top, left side perspective view of a cylinder release button showing our new design;

FIG. 2 is a rear, bottom, right side perspective view thereof;

FIG. 3 is a front, elevation view thereof;

FIG. 4 is a rear elevation view thereof;

FIG. 5 is a left side, elevation view thereof;

FIG. 6 is a right side, elevation view thereof;

FIG. 7 is a top, plan view thereof; and,

FIG. 8 is bottom, plan view thereof.

The broken lines in the figures are used to illustrate environment and unclaimed parts, in which the claimed design is embodied, and form no part of the claimed design.

1 Claim, 8 Drawing Sheets
